UNITED STATES PATENT OFFICE

149,454

DESIGN FOR A BODY FOR TRAILER VEHICLES

James Stephen, Edgerton, Wis., assignor to Highway Trailer Company, Edgerton, Wis.

Application September 27, 1946, Serial No. 133,611

Term of patent 14 years

(Cl. D14—3)

To all whom it may concern:

Be it known that I, James Stephen, a citizen of the United States, residing at Edgerton, in the county of Rock and State of Wisconsin, have invented a new, original, and ornamental Design for a Body for Trailer Vehicles, of which the following is a specification, reference being had to the accompanying drawing, forming part thereof, wherein:

Figure 1 is a perspective view of a body for trailer vehicles, showing the design of my invention.

Figure 2 is a side elevation.

Figure 3 is a front elevation.

Figure 4 is a fragmentary top plan view.

I claim:

The ornamental design for a body for trailer vehicles, substantially as shown.

JAMES STEPHEN.
